UNITED STATES PATENT OFFICE

151,905

DESIGN FOR A CLOCK THERMOSTAT

Carl G. Kronmiller, Edina, Minn., assignor to
Minneapolis-Honeywell Regulator Company,
Minneapolis, Minn., a corporation of Delaware

Application April 14, 1947, Serial No. 138,361

Term of patent 14 years

(Cl. D52—7)

To all whom it may concern:

Be it known that I, Carl G. Kronmiller, a citizen of the United States residing at Edina, in the county of Hennepin and State of Minnesota, have invented a new, original, and ornamental Design for a Clock Thermostat, of which the following is a specification, reference being made to the accompanying drawing, forming part thereof and in which

Figure 1 is a perspective view of a clock thermostat embodying my new design, looking from the top and to the right; and

Figure 2 is a perspective view of the same, looking from below and to the left.

I claim:

The ornamental design for a clock thermostat, substantially as shown.

CARL G. KRONMILLER.
